(57) **CLAIM**

The ornamental design for a computer microphone, as shown and described.

DESCRIPTION

FIG. 1 is a plan view of computer microphone showing my new design;

FIG. 2 is a front view thereof;

FIG. 3 is a rear view thereof; and

FIG. 4 is a left side elevational view thereof;

FIG. 5 is a right side elevational view thereof;

FIG. 6 is a top elevational view thereof; and,

FIG. 7 is a bottom elevational view thereof.
